UNITED STATES PATENT OFFICE

JOHN THOMSON, OF NEW YORK, N. Y.

ELECTRIC ZINC-FURNACE WITH INTEGRAL CONDENSER.

1,086,414.

Specification of Letters Patent. Patented Feb. 10, 1914.

Application filed January 2, 1913. Serial No. 738,730.

To all whom it may concern:

Be it known that I, JOHN THOMSON, a citizen of the United States, and a resident of the borough of Manhattan of the city of New York, in the county and State of New York, have invented certain new and useful Improvements in Electric Zinc-Furnaces with Integral Condensers, of which the following is a specification, reference being made to the accompanying drawings, forming a part hereof.

This invention relates to the metallurgy of zinc, and its object is to produce by a thermo-chemical reaction zinc fume which is subsequently condensed to liquid metal.

A description of the particular means for attaining the desired results and such an elucidation of such general principles applicable thereto as seem necessary for a complete disclosure of the invention are set forth in this specification, reference being had to the accompanying drawings forming a part of said specification and in which drawings a specific embodiment is illustrated.

In said drawings Figure 1 is a transverse center section of the furnace viewed either as A or A¹ of Fig. 2, the charge on the right hand side being omitted. Fig. 2 on the lower or left hand side of its center line is a vertical longitudinal section as on the line B of Fig. 1, while that portion on the upper or right hand side of its center line is a vertical longitudinal center section, as C or C¹ of Fig. 1. Fig. 3 is a partial top plan view, as on the horizontal planes D, D¹ of Fig. 1; and Fig. 4 is a diagrammatic illustration relating to a detail of the operation.

This furnace is particularly intended for the reduction of igneous oxid of zinc combined with carbon as the reagent, whereby, when adequately heated, substantially the following representative reaction ensues, namely:

If pure ZnO and C are used in precisely correct relative proportions, then the answer of the above formula is an exact expression of the result, in that all of the charged material would be volatilized as zinc fume and monoxid of carbon, whence there would be no residue, but such conditions do not obtain in commercial practice because more or less of inert residual matter will remain, the

amount of this residual matter manifestly depending upon the purity of the materials employed. Therefore, in actual commercial practice the formula becomes simply representative, as above stated. The presence of residual matter even in small quantities is a cause of more or less difficulty in realizing the desired result.

The heat necessary for decomposing the charge is preferably derived from an electric current passed through a broken bed of carbon "resistor", the charge being acted upon by direct conduction of heat. Two of such resistors, H, H¹, are preferably employed, each being interpolated between terminals, as 6, to which the electric current is conducted by suitable copper electrodes 7, 7¹. These two resistors above may be electrified from separate circuits or may be in parallel in the same circuit or may be in series in the same circuit, as may be desired. Each resistor is contained in a basin-like chamber m, widest at the top, and is supported upon a series of spaced members 8, providing a grate beneath which is a hearth space or sump n, whose function is to receive inert residual matter, as 9. The object of thus forming the resistor approximately wedge-like in cross section is to produce a greater thermal dispersion through its upper zone from which the charge receives its heat.

The condenser J is disposed midway between the resistors or along the longitudinal center of the furnace.

Along the sides of the resistor but above its face are a series of outer and inner ports 10, 12, whose intervening pillars, as 13, serve to support the roof tiles or bricks 14 which overlie the resistors, and to support the spacers 21 and the bricks therefor which provide the condenser roof. The spaces between the top surfaces of the resistors and the lower surfaces of the roof tiles are designated the reaction chambers. The outer furnace walls 15 are built so as to leave inner side galleries 16 open at their tops and in these walls are also provided a series of openings or ports 17 in axial alignment with the reaction chamber ports 19.

The composite charge in reserve, as P, is placed upon the tops of the resistor covers or roof and into the aforesaid side galleries. It will thus be perceived that it is simply necessary to stoke the charge material, as

by means of rods, from the bottoms of the galleries into and through the outer ports 10, so as to force it upon the incandescent faces of the resistors. When the stoking bar 5 is withdrawn the material in the side galleries automatically takes up its displacement, thus sealing the ports 10 against the escape of fume or gas. The tiles which overlie the reaction chambers are preferably kept 10 covered with reserve charge material which serves to conveniently supply the side galleries, to seal the tile or brick joints and also to absorb whatever heat that may be emitted through and between the tiles to the charge. 15 The latter, however, will not be of much consequence, as the upper surfaces of the material charged upon the faces of the resistors are colder than the exposed inner surface of the tiles and consequently the 20 heat received by the tiles is radiated from the said surfaces.

The charge, as stoked upon the faces of each of the resistors, may ordinarily be as diagrammatically denoted in Fig. 3. That 25 is, it will tend toward a transverse ridge formation having between the ridges troughs or trenches 18 from whence the evolved fume and gas may find ready escape, as in the manner indicated by the flow arrows, and thus rise into the free space of the 30 reaction chamber. From the free space in each of the reaction chambers on the opposite sides of the condenser the evolved fumes and gases can pass or flow directly through 35 the inner ports 12 to the receiving chamber 19 at the top of the condenser. As shown on the left hand sides of Figs. 1 and 3 the fume ports 12 may be filled with coke whereby if any CO_2 is produced by the primary 40 reaction it may thus be eliminated by a secondary reaction. The passing of the products of the reaction through the coke in the ports 12 is to produce what may be termed "clean" 45 fume and pure CO when delivered into the condenser. The secondary reaction coke is readily placed in position and renewals may conveniently be made by simply removing the bricks and tiles which form the roof portion of the ports.

50 When using igneous ZnO of fairly good quality and reaction coke with a minimum of ash the residue will be comparatively small and only a nominal volume and usually in the form of a caked sinter which 55 is easily disintegrated. This sinter may be broken up during certain interim periods as by a slicing bar and in fact if desired may be partially removed as by scraping or raking the surfaces of the resistors through the 60 stoking ports. At longer periods the overhead tiles may be removed and the resistor may be poked from above as by means of pointed bars. In the ways above referred to the residue 9 will be caused to pass down 65 through the grate bar spaces and collect in

the sump n, from whence at yet even longer periods it may be withdrawn as through the sump opening 20.

The top of the condensing chamber is covered with spanner tiles as 21 and above these 70 ordinary bricks are set sufficient to insure effective heat insulation, and as previously stated, these tiles and bricks provide the roof of the condenser.

The bottom of the condenser is utilized as 75 a zinc reservoir R in which is a bath of molten metal 22. The space intervening between the receiving chamber and the zinc reservoir is sub-divided by several series of closely set rods 23 supported upon plates 24, 80 thereby forming horizontal passages e. Each series of rods does not extend the full length of the chamber but in or for each series free openings or ports are provided. Thus, in one series there is one port in the center as 85 at 25, while for the next or underlying series there are provided two ports, one at each end, as at 26. The roofs and floors of the said passages may be termed "corrugated" and the side joints between the closely set 90 rods are not tight.

The function of the receiving chamber 19 is to permit a certain expansion of the incoming fume and gas and to cause equalization of pressure and volume. As is indicated by the flow arrows, the hot fume and gas in the receiving chamber finds its course of least resistance down through the center port 25, thence it splits and flows right and left along the passage e, then passes down 100 through the end ports 26 and again flows each volume toward the other, until the second center port 25^a is reached, when a traverse similar to that above described is repeated to such an extent as is required. 105 The final delivery, however, is to be through a center or end ports into the zinc reservoir, whence the face of the bath must be traversed. It will be perceived that as a certain amount of pressure is imparted to the flowing gases a portion thereof will find its way through the slits which will exist between the rods even though they are closely set, and also that the fume as it is condensed must necessarily settle or collect in the corrugations of the floors and percolate through the aforesaid slits. The consequence of the foregoing is that the fume and gas traversing the horizontal flues or channels will be pierced by a great number of vertical sheets 110 or jets of fume and gas and also of condensed globules of liquid zinc, the effect of which is highly conducive to complete condensation of fume floating in an "atmosphere" of CO. As the several rows of rods 115 are in physical contact with the supporting plates 24 and as the lowermost series of these supporting plates, 24^a, is immersed in the bath, the fall in temperature between the receiving chamber and the bath is progres- 120 125 130 135

sive. From an inspection of the drawings, and especially Fig. 2 thereof, it will be observed that the several rows of rods constitute horizontal shelf-like members and provide between said shelves the horizontal channels through which zinc fumes flow in a sinuous transit through the receiving chamber. From the last horizontal channel it will be noted that at least a part of the 10 gaseous fume impinges upon the bath of molten zinc in the bottom of the condenser and all of the fume which leaves the condenser must pass over and in the presence of the liquid bath. If the rods are formed of amorphous carbon and the supporting plates of graphite, the downward flow of the heat extracted from the fume and gas may be provided for to any desired extent. It is important that this considerable difference in temperature shall not be subject to serious fluctuations and such a condition is insured by providing a chamber or flue 20 I beneath the zinc reservoir, whose function is to control the temperature of the bath by the introduction of heat or cooling air, as the case may be, through suitable openings or tubes 27, 27^a.

Any residual of gas or fume, after traversing the face of the bath, finds exit through the ports 28, 29, to chambers T, T¹, and thence to atmosphere from the tubes 30, 30^a. These chambers lie parallel to the lower portion of the condenser and immediately beneath the resistors so that the heat carried 30 therein by the gases acts to conserve the heat in the resistor hearths and also in the sides of the condenser.

Various modifications might be shown, but as the drawings are indicative of general principles of construction rather than of precise working details, it has not been deemed necessary to visually denote that structural alterations may be made without departing from the spirit and essence of the 45 present disclosure.

What I claim is:

1. In an electric zinc furnace, a bed-of-carbon resistor which in cross section is widest at its upper or reacting surface. 50 2. In an electric zinc furnace a bed-of-carbon resistor, an inclosed reaction chamber provided with a series of openings or ports extending above the resistor and in the side walls of the reaction chamber, through which openings or ports the charge is stoked to and upon the upper surface of said resistor.

3. An electric zinc furnace having therein a bed-of-carbon resistor, an inclosed reaction 55 chamber and in the walls thereof a series of side openings or ports through which the charge is passed to and upon the upper surface of the resistor.

4. In an electric zinc furnace, a bed-of- 60 carbon resistor, an inclosed reaction chamber

and a series of separated openings or ports through which the charge is stoked in the form of transverse ridges alternating with troughs or trenches to and upon the upper surface of said resistor.

5. An electric furnace having a bed-of-carbon resistor in an inclosed reaction chamber and a charge thereupon in ridge or pyramidal formations when the reaction is taking place.

6. An electric-zinc furnace having a bed-of-carbon resistor contained in an inclosed reaction chamber having a free space above and into which all of the volatilized products of the reaction must ascend, said furnace being provided with side openings or ports for conducting said volatilized products of the reaction to a condenser.

7. The combination of a bed-of-carbon resistor in an inclosed reaction chamber of an electric furnace and condenser arranged parallel to the resistor, there being side ports or openings leading from the upper inferior portion of the reacting chamber to the chamber of the condenser.

8. In a combined electric furnace a condenser, a bed-of-carbon resistor contained in a reaction chamber being spaced above and into which the volatilized products of the reaction may ascend and from which said products may pass through side openings or ports into the condenser.

9. In an electric zinc furnace, a bed-of-carbon resistor, an inclosed reaction chamber, a condensing chamber parallel to said resistor, and a series of connecting openings or ports filled with broken carbon and through which ports the volatilized products of the reaction must pass, the ports being arranged so that they do not extend below the top of the resistor.

10. An apparatus of the class described, having in an inclosed reaction chamber the bed-of-carbon electric furnace resistor, a condenser arranged adjacent to the reacting chamber and provided with passageways through which the products of reaction can pass from the upper portion of the reaction chamber to the upper portion of the condenser.

11. A condenser adapted to receive from one or more sources of supply the volatilized products of the reaction of an electric furnace or electric furnaces, said condenser having horizontal shelf-like members which provide a series of superposed communicating horizontal channels through which the gaseous fume flows during its passage in a sinuous path through the receiving chamber of the condenser, the condenser also being provided with a bath of molten zinc with which the fume impinges and over which the fume passes prior to leaving the condenser.

12. In an electric zinc furnace a condenser adapted to receive the volatilized products

- of the reaction from a plurality of sources of supply, said condenser being provided with a series of substantially horizontal condensing members arranged at different elevations and providing therebetween horizontal channels for receiving the products of the reaction as they flow from the condenser in a sinuous or indirect path, said condenser also being constructed so that the residual products of the reaction will finally pass over a metal bath located under the horizontally extending condensing members above referred to and in the same chamber therewith.
- 15 13. An electric zinc furnace provided with a condenser adapted to receive from one or more sources of supply the volatilized products of the reaction, which thereafter traverse a series of superposed horizontal channels whose roofs and floors are formed of adjacent rods.
14. In an electric zinc furnace, a condenser adapted to receive in the upper portion thereof, from one or more sources of supply, the volatilized products of the reaction, said condenser being provided with a series of superposed horizontal flow channels which are defined by rods that form the roofs and floors of said channels.
- 20 15. A combined electric furnace and condenser having in the condensing chamber partitions providing therebetween flow channels and which partitions comprise a series of closely arranged rods that extend transversely to the path of flow.
16. An electric zinc furnace comprised of two parallel bed-of-carbon resistors, an interposed condenser, a roof or cover common to all and a compound series of ports immediately beneath the roof, through one set of which the charge is stoked upon the upper surfaces of said resistors and through an-

other set of which the volatilized products of the reaction pass to the said condenser.

17. A combined electric furnace and fume condenser in which there is located a bed-of-carbon resistor in the lower portion of the reaction chamber and in which there is provided in the path of the flow of the fumes from the resisting chamber to the top of the condensing chamber a carbon screen or filter, which is located at a higher elevation than the resistor.

18. A combined electric furnace and fume condenser in which there is located a bed-of-carbon resistor in the lower portion of the reaction chamber and in which there is provided in the path of the flow of the fumes from the resisting chamber to the top of the condensing chamber a carbon screen or filter, which is located at a higher elevation than the resistor, the condenser being constructed so that any residual fumes will pass to a space in the furnace directly below the resistor.

19. A combined electric furnace and zinc condenser in which the residual products leaving the condenser pass directly to a space under the reaction chamber.

20. A combined electric furnace and zinc condenser, a molten zinc receptacle at the bottom of the condenser, a chamber or flue beneath the condenser and means for heating or cooling the said chamber or flue, whereby the temperature of the molten zinc may be controlled according to the rate of evolution of zinc fume.

This specification signed and witnessed this 31 day of December A. D. 1912.

JOHN THOMSON.
